UNITED STATES PATENT OFFICE.

GRANT G. GARD, OF OVERTON, NEBRASKA.

BOX-STRAP.

1,367,038.

Specification of Letters Patent.

Patented Feb. 1, 1921.

Application filed September 21, 1917. Serial No. 192,553.

To all whom it may concern:

Be it known that I, GRANT G. GARD, a citizen of the United States, residing at Overton, in the county of Dawson and State 5 of Nebraska, have invented new and useful Improvements in Box-Straps, of which the following is a specification.

This invention relates to means for securing the fastenings of wooden packing boxes 10 or cases by means of metal straps, in a manner to permit of the strap being removed and again secured to the same or another box or case.

The invention contemplates novel means 15 for securing the strap around the box, the said means providing for tightening the strap upon the box at the same time that it is secured thereon.

The invention therefore consists of a bar 20 or lever pivotally secured to one end of the strap and provided with spaced elongated openings which are adapted for removable engagement when the bar is at an angle to the strap, with the elongated element in the 25 form of a stud or rivet, the said stud or rivet being held against removal within the openings when the bar is alined with the strap. The swinging of the bar into alinement with the strap acts as a lever and 30 serves to tightly bind the strap around the box or case, the bar being held in such alinement by a band movable along the strap and engageable over the end of the bar. Means are also provided for preventing the 35 accidental removal of the band, which consists of a nail or other pointed and headed element driven into the box and passing through the opening in the band and engaging the notch in the bar.

40 In the drawings,

Figure 1 is a perspective view of one end of a packing case or box equipped with the invention;

Fig. 2 is a similar view of the adjacent 45 ends of the metal band in a position prior to the engagement of one end of the band with the pivot bar;

Fig. 3 is an enlarged sectional view on the line 3—3 of Fig. 1;

50 Fig. 4 is a transverse sectional view on the line 4—4 of Fig. 1;

Fig. 5 is a similar view on the line 5—5 of Fig. 1; and

Fig. 6 is an inverted plan view of the end

of the band carrying the elongated stud or rivet.

In the drawings there is illustrated one end of a packing case or box, such as is commonly employed for the shipment of eggs, although it is understood that the invention 60 is susceptible of various uses, for example, it may be used as a substitute for leather straps upon trunks or as an emergency barrel hoop, or for various other purposes.

Secured around the packing case is a 65 strap 10, preferably formed of thin metal and of a length to pass entirely around the box and slightly overlap when secured in position thereon. One end of this strap has pivoted thereto as shown at 11 a bar 12 of 70 relatively heavy material, this bar serving as a lever as will be hereinafter apparent.

The bar 12 has formed therein a plurality of elongated openings 13, preferably elliptical in form and spaced apart as shown. 75 While there is illustrated five of such openings, it is obvious that any suitable number may be employed. The openings 13 are designed for engagement with a stud or rivet 14 secured to the opposite end of the strap 10, this stud or rivet being spaced from the bottom face of the said strap and being provided with a head 15 of substantially the same shape as the openings 13, so that it may be inserted in any one of these openings.

When the parts are in the position shown in Fig. 2, the head 15 may be placed within any of the openings 13, the bar 12 entering the space formed between the head and the 90 strap 10. When in this position the bar 12 may be utilized as a lever and by swinging around into alinement with the end of the strap to which it is secured, thereby tightening the band upon the case and preventing 95 the head 15 from passing through the opening 13.

The bar 12 is provided at the end opposite the pivot 11 with an opening 16, which when the bar is positioned over the strap 10 is adapted to register with the opening 17 formed in the said band and when in this position a flat headed nail or screw may be inserted into these openings in the packing case to hold the bar against lateral movement.

To further secure the bar 12 in position and to prevent the unauthorized movement

of the nail or screw, the strap 10 has slidably mounted thereon a band 18, which is adapted to engage over the end of the bar 12 and cover the head of the before mentioned nail or screw. The band 18 is provided with openings 19 and 20, disposed out of alinement, these openings being adapted to register with a notch 21 formed in the strap 10, when the said band is in position. 5
10 The bar 12 is provided with an additional opening 22, which is adapted to aline with the openings 19 and 20 of the notch 21, so that by driving a nail 23 or other suitable sharp instrument into the packing case the 15 band 18 will be held against movement.
It is believed that from the foregoing description when taken in connection with the accompanying drawings, the construction, operation and advantages of the invention 20 will be apparent. The right is reserved to

make such changes in the form and proportion thereof as will fall within the scope of the claim hereto appended.

Having described the invention, what is claimed is:

25 A device of the class described embodying a metal strap, a bar having one end positively pivoted to one end of the strap, said bar being provided with elongated apertures intermediate its ends, a laterally extending stud carried by the opposite end of the strap, an elongated head positioned upon the outer end of the stud for removable engagement with said apertures when the bar is swung at an angle to the strap 30 and held against removal when the bar is alined with said strap and means for holding the bar in alinement. 35

In testimony whereof I affix my signature.
GRANT G. GARD.
